UNITED STATES PATENT OFFICE

2,504,773

MOISTENING DEVICE

Forrest J. Williams, San Francisco, Calif., assignor of sixty per cent to Edna Hein, San Francisco, Calif.

Application November 29, 1946, Serial No. 712,792

1 Claim. (Cl. 91—27)

1

This invention relates to an improved moistening device and has particular reference to a specially constructed device for use in moistening envelope flaps, stamps and other articles coated with adhesive, whereby the adhesive is softened and becomes sticky for sealing the material to the surface intended.

An object of the present invention is to provide a suitable open container forming a reservoir for retaining the desired amount of liquid therein and to provide an enlarged lower roller and a smaller upper roller and to operatively arrange the said rollers in such relation to each other as will cause the peripheries thereof to be in rolling contact, the periphery of the lower roller dipping into the well, whereby a thin film of fluid is carried upward to and in between the peripheries of the rollers for moistening the adhesive on such articles as envelope flaps for sealing the same.

Another object of the present invention is to revolvably support the lower roller in the top surface of the container and to provide a removable clamp on the said container forming a standard that extends upwardly to and around the upper roller for revolvably supporting the said upper roller and retaining the same in the proper operative position relative to the lower roller.

A further object of the present invention is to form oppositely opposed vertical slots in the upper projecting members of the standard for receiving and supporting the shaft of the upper roller, whereby the said roller is free to rise and move vertically for accommodating different thicknesses of adhesive coated materials to be moistened.

A still further object of the present invention is to knurl or otherwise roughen the outer periphery of the upper roller to facilitate the movement of the adhesive coated materials projected between the rollers.

A still further object of the present invention is to provide a suitable brush or the like directly above the upper roller and secure the same to the standard to function as an auxiliary spreader and to remove surplus fluid from the materials when necessary.

A still further object of the present invention is to provide a moistening device of the character described that is durable, simple in construction, economical to manufacture, positive in operation and highly efficient and serviceable in use.

2

Other objects and advantages will be apparent during the course of the following description.

In the accompanying drawings forming a part of the specification, wherein for the purpose of illustration like numerals designate like parts throughout the same,

Fig. 1 is a top plan view of the improved moistening device,

Fig. 2 is a vertical sectional view taken 10 through line 2—2 of Fig. 1 looking in direction of the arrows A, and

Fig. 3 is a vertical sectional view taken through line 3—3 of Fig. 1 looking in direction of the arrows B.

15 Referring in detail to the drawing and to the numerals thereof the numeral 5 designates as a whole a container, preferably rectangular in shape with vertical walls 6, 7, 8 and 9 and a horizontal bottom 10 forming a suitable reservoir 11 as shown in Figs. 1 and 2. The top surface of the walls 8 and 9 of the container are formed with oppositely opposed grooves 12 for receiving and supporting a suitable shaft 13, which shaft horizontally extends through an 20 enlarged roller 14 as shown in Fig. 3. The said shaft is preferably fixed to the said roller 14 and the said roller preferably extends in the reservoir 11 of the container as shown in Fig. 2.

A standard designated as a whole by the 25 numeral 15 is formed with a bottom 16, oppositely opposed vertical end walls 17 and 18, which end walls extend inwardly and over the top surface of the container walls 8 and 9 as at 19 and 20. The said standard is preferably 30 formed of a suitable spring metal or plastic and is tightly clamped to the said container and is further provided with upper vertical walls 21 and 22 and a horizontal top wall 23 and a downwardly extending wall 24 as shown to advantage 35 in Fig. 3. The said walls 21 and 24 terminate a short distance from each other at the top of the roller 14, whereby a space 24' is formed for enabling the adhesively coated material to be inserted between the peripheries of the rollers.

40 A roller 25 of smaller diameter than the roller 14 is positioned on the upper peripheral extremity of the said roller 14 and is provided with a fixed shaft 26, which shaft is revolvably supported in oppositely opposed slots 27 and 28 provided in the upper walls 22 and 24. The peripheral surface of the smaller roller 25 is knurled or roughened as at 29 to facilitate the movement of the materials projected between the rollers. The numeral 30 shown in dot and dash 45 lines designates a piece of material such as an 50

55

envelope flap coated with an adhesive substance on the other side, when the material is positioned between the rollers and is pulled past the same, the weight of the top roller 25 resting on the said material 30 and lower roller 14 will cause revolable movement to be imparted to the rollers whereby fluid from within the reservoir 11 will be carried on the lower roller 14 to moisten the adhesive coating on the said material. As the smaller upper roller 25 is positioned in the oppositely opposed slots 27 and 28 and rides on the periphery of the lower roller 14 it will be obvious that the said smaller roller will raise when the material to be moistened is inserted between the rollers, whereby different thicknesses of materials are accommodated.

A brush 31 having a back 32 is fixed to the top face of the cross member 23 of the standard and is provided as an auxiliary spreader to be used in conjunction with the rollers when it is desired to go over the adhesive substance to evenly spread the moisture thereon and also to remove any surplus fluid on the coated materials when necessary. The said materials are merely taken from between the rollers and immediately rubbed over the brush to accomplish the purpose intended.

The container 5 and the rollers 14 and 25, respectively, are shown as being constructed of porcelain but can be made of plastic or any other suitable material.

It is to be understood that the form of my invention herewith shown and described is to be taken as a preferred example of the same and that various changes relative to the shape, size, material and arrangement of parts may be resorted to without departing from the spirit of the invention or the scope of the subjoined claim.

Having thus described my invention, I claim:

A device of the character described for use in moistening the adhesive coated substance for envelope flaps and the like, comprising a container forming a fluid reservoir with an open top, a lower roller revolvably supported on the upper portion of the container and extending in the said reservoir, an upper roller resting on the periphery of the lower roller and positioned in parallelism therewith, the said upper roller being of a smaller diameter than the lower roller, a shaft horizontally fixed to the upper roller, and a standard in the form of a spring clamp surrounding said container and said rollers, and a pair of oppositely opposed vertical guide slots in the said standard capable of receiving and slidably supporting the said shaft, said standard embodying in its construction a base portion positioned beneath said container, upwardly extending side arms, and a top portion integrally formed with said base portion and terminating in a vertical side wall, said top portion being spaced from said upper roller, lying in parallelism therewith and capable of supporting thereon a brush for spreading moisture on the adhesive coated envelope flaps and to remove excess fluid therefrom, the last mentioned horizontal shaft being journaled in the vertical arms of the said brush supporting standard.

FORREST J. WILLIAMS.
